UNITED STATES PATENT OFFICE.

ALEXANDER T. KOPPE, OF LOS ANGELES, CALIFORNIA, ASSIGNOR TO OFFSET DIRECTO-PLATE COMPANY, OF CHICAGO, ILLINOIS, A CORPORATION OF ILLINOIS.

VACUUM-PRESSURE FRAME.

1,396,962.

Specification of Letters Patent. Patented Nov. 15, 1921.

Application filed November 5, 1919. Serial No. 335,968.

To all whom it may concern:

Be it known that I, ALEXANDER T. KOPPE, a citizen of the United States, residing at Los Angeles, in the county of Los Angeles and State of California, have invented certain new and useful Improvements in Vacuum-Pressure Frames, of which the following is a specification.

This invention relates to an improvement 10 in vacuum pressure frames for photographic negatives, and particularly to a pressure frame for securing the negative in contact with a surface on which the negative is to be photographically reproduced, as for example, the press plate of a machine for making offset press plates.

In making offset press plates, particularly as described in connection with Patent No. 1,277,429, issued to me September 3, 1918, 20 the negative is applied directly to the press plate for reproduction, and this requires a means for positively fixing the negative in close contact with the press plate. The means described in such patent included a 25 heavy glass member, applied directly to the negative with desired pressure. This pressure plate exerted an even pressure on and throughout the negative, and in the event the negative was slightly warped or distorted, an almost certain breaking of the 30 negative resulted.

The present invention is designed to entirely overcome the liability of breaking the negative, and this without sacrificing 35 any of the advantages of the previously necessary heavy pressure plate. The improved pressure plate comprises two frames, one to rest on the press plate, and having an inner marginal edge within which the negative is 40 to be placed, and a second frame to rest on the marginal edge of the first frame and on the edge of the negative. The air is then exhausted from beneath the second frame and inner marginal edge of the first frame, causing 45 the negative to be held with proper pressure on the press plate. As the inner section, or negative bearing frame engages only the marginal edge of the negative, and is itself particularly constructed to compensate 50 for irregularities, there is no liability of breaking the negative, nor of sacrificing that

close contact of the negative and press plate necessary for proper reproduction.

In the drawings:—

Figure 1 is a view of the outer or pos- 55 titioning frame section of the improvement.

Fig. 2 is a section on line 2—2 of Fig. 1.

Fig. 3 is a plan of the inner or bearing frame section of the improvement.

Fig. 4 is a section on line 4—4 of Fig. 3. 60

Fig. 5 is a plan showing the improved frame applied to a press plate.

Fig. 6 is an enlarged section, on the line 6—6 of Fig. 5.

The improved vacuum pressure frame, as 65 here shown, comprises an outer frame section 1, hereinafter termed the positioning section, and an inner frame section 2, herein- after termed the bearing section.

The positioning section is of open rectangular construction, the sides and ends being of bar form, as at 3. The lower side or surface of the positioning section is formed adjacent the outer edge with a channel 4 to receive a sealing strip 5, preferably of rubber, and inwardly of the channel 4 is cut away to form an air-channel 6. Projecting inwardly and in line with the bottom of the section is a lip or flange 7, the inner edge of 75 which defines the opening within the positioning section for receiving the negative.

The bearing section 2 is made up of a more or less flexible strip 8 of rectangular outline, that is with side and end bars. The lower surface of this strip is channeled at 9, the 85 channel extending longitudinally of each side and end bar and merging one into another, so that the channel extends uninterrupted throughout the linear length of the section. This channel 9 is preferably reinforced to prevent collapse or distortion by a thin metallic strip 10, as shown, and the upper surfaces of the end and side bars making up the section are also provided with reinforcing strips 11 of metal or the like. A 90 particularly important feature of the reinforcing of the channel 9 and of the end and side bars, is that the reinforcing strips in both instances terminate adjacent but free of contact with the adjacent reinforcing 100 strip. This, as will be apparent, provides a substantial reinforce, but yet avoids that ri-

gidity of the frame or section which would result from a complete and uninterrupted reinforcing. The meeting portions of the side and end bars are thus wholly free of reinforcing, and hence to a limited extent will permit independent yielding or distortion of the side and end bars.

When applied to the press plate, as 12, which in turn is supported on a base plate 10 13, resting on a foundation 14, the positioning frame 1 is applied directly to the face of the press plate so as to outline that portion of such press plate to be occupied by the negative. It will be understood that certain 15 registry marks are arranged on the press plate for correct placement of the negative. The negative 15 is then applied, in proper position within the flange 7, and directly on the press plate. In this position, it will be 20 noticed that the interior dimensions of the flange 7 are somewhat greater than the exterior dimensions of the negative, to thereby permit adjustment of the negative as may be indicated by the register marks, without 25 disturbing the positioning section 1. The positioning frame is designed to rest upon the press plate, or more exactly to be supported by the sealing strip 5, so that the bottom of the positioning section inwardly of 30 the sealing strip is spaced from the surface of the press plate, and the upper surface of the flange 7 substantially in line with the upper surface of the negative. It is therefore preferred that the section 1 be comparatively heavy, and for this result such section 35 is made of metal.

Following the proper positioning of the negative, the bearing section 2 of the improved frame is applied, with the lower surface 40 face margin outwardly beyond the channel 9, resting on the flange 7 of the section 1, while the lower margin surface inwardly of the channel 9 rests on the negative, near the edge thereof. The junction of the section 1 45 with the press plate is sealed by the strip 5, while the space between the flange 7 of the section 1 and the negative is sealed by the bearing section 2. The air is then exhausted from beneath the section 1 inwardly of the 50 sealing strip 5, as by a suction apparatus (not shown), the tube 16 from which extends through the bar of the section 1, and may, if preferred form a more or less permanent part thereof. This exhaustion of the air 55 causes the bearing section 2 to press upon the flange and negative and force the latter into that close contact with the press plate necessary for proper results.

The relative yielding between the end and 60 side bars of the section 2, are important, as thereby any warped condition of the negative, expressed in a distortion of its edge, or any irregularities of the flange 7 will be compensated for in the relative movement of

the particular portion of the section 2, and 65 this without disturbing the other sections.

The bearing section 2 is preferably, aside from the reinforcing portions, constructed of a single rubber section cut or molded to proper form, and while the frame sections 1 70 and 2 are here shown as of rectangular outline, it is apparent that any outline form is contemplated. The positioning section may be provided with lugs 17 for convenience in handling such section. 75

The invention is illustrated and described particularly in connection with securing a negative in position on a press plate, and while of improved result in such use, the vacuum pressure frame of this invention is 80 of course of such construction as to adapt it to other uses in negative holding than the one specifically shown and referred to. 85

Having thus described the invention, what is claimed as new, is:—

1. A vacuum pressure device for a photographic plate disposed on a plate support, said device comprising a frame, spaced sealing members carried by said frame, one of said sealing members being positioned to engage the plate adjacent its marginal edges, the other sealing member being positioned to engage the plate support and means of communication for exhausting the air from beneath the frame. 90

2. A vacuum pressure frame for negatives, comprising frame sections to rest upon the negative support and on the negative, means for sealing the coöperation of the frame sections with said support and with 100 the negative, and means of communication for exhausting the air from beneath the frame sections. 100

3. A vacuum pressure frame for negatives, comprising a positioning frame section to rest upon a support for the negative, a bearing frame to rest on said negative and on the positioning frame, and means of communication for exhausting the air from beneath said frames. 105

4. A vacuum pressure for holding negatives in fixed relation to a surface for reproduction, comprising a positioning frame section to rest on said surface beyond the negative-engaging portion thereof, a bearing frame section to rest on said positioning frame and negative, and means of communication for exhausting the air from the space underlying the bearing frame section. 115

5. A negative pressure frame, comprising 120 a two-part frame, one part being adapted to be arranged beyond the edge of the negative, and the other part being adapted to bear on the first mentioned part and on the negative adjacent the edge thereof. 125

6. A two-part negative pressure frame, comprising a section adapted to surround the edge of the negative, a section to rest on

- said first section and on the negative, and means of communication for exhausting the air from below said sections.
7. A two part negative pressure frame, comprising a section to surround the negative in spaced relation to the edge thereof, a second section of an outline form corresponding to the outline form of the negative, said second section being adapted to rest on the first mentioned section and negative, the second section having sealing coöperation with the first mentioned section and with the negative.
8. A two part negative pressure frame, comprising a positioning section within which the negative is arranged, a sealing strip carried by the positioning section to engage the support on which the negative is to be held, and sealing strips carried by the bearing section to engage the positioning section and negative.
9. A two part pressure frame for negatives, comprising a positioning section, and a bearing section, said bearing section being of yieldable material and of outline form, and reinforcing strips secured to the bearing section except at predetermined portions thereof, whereby the bearing is rigid for bearing purposes while being also yieldable at the non-reinforced portions.
10. A two part pressure frame, comprising a positioning section, and a rubber bearing section of outline form having reinforcing strips secured thereto except for predetermined portions, as and for the purposes stated.
11. A two part pressure frame, comprising a positioning section, and a rubber bearing section of rectangular form having a channel in the under surface, and reinforcing strips for said section terminating short of the corners thereof.
12. A vacuum pressure frame to secure a negative on a press plate, comprising a positioning frame to rest upon said press plate, a bearing frame to engage said positioning frame and the negative adjacent the edge thereof, and means of communication for exhausting the air from between said frames and press plate.
13. A vacuum pressure frame to secure a negative on a press plate, comprising a positioning frame of negative outline form to rest on the press plate to define the negative receiving area thereof, said frame having a lip arranged just beyond the negative edge when in position, and a means for sealing the junction between the lip and negative to permit air exhaustion from beneath such frame, said means bearing on the negative with a pressure proportionate to the degree of vacuum.
14. A vacuum two part pressure frame, comprising a positioning frame section, a sealing strip secured to the lower edge thereof, a lip projecting from the inner edge thereof, and a bearing frame section having spaced sealing portions projecting from the lower surface thereof.

In testimony whereof I affix my signature. 70

ALEXANDER T. KOPPE.
